COPY HOLDER

Arthur G. Croninger and Olaf D. Baker,
Miami, Okla.

Application July 14, 1937, Serial No. 153,643

1 Claim. (Cl. 120—28)

The present invention aims to provide a copyholder characterized by the provision of a novel paper clamping device, the construction being such that the material copied can be held in 5 a variety of adjusted positions with respect to the operator.

In the drawing:

Fig. 1 shows in front elevation, a device constructed in accordance with the invention;

10 Fig. 2 is a side elevation;

Fig. 3 is a section on the line 3—3 of Fig. 2, parts being omitted;

15 Fig. 4 is a section on the line 4—4 of Fig. 2, parts being omitted.

In carrying out the invention, there is provided a support S, on which is mounted a table 25.

A track 28 is secured to the rear surface of the table 25, near to one longitudinal edge of the table. A slide 29 is mounted for vertical reciprocation on the track 28. A pivot element 31 connects a carrier 30 to the slide 29. The axis of the pivot element 31 is at right angles to the table 25, and the carrier 30, therefore, can turn about that axis.

20 Ears 32 are extended rearwardly from the carrier 30. A shaft 33 is journaled in ears 32 on the carrier 30. At one end, the shaft 33 is provided with a rectangularly disposed arm 34, which is upwardly extended. The arm 34 is provided at 25 its upper end with a part 35 which extends forwardly above the upward edge of the table 25. The part 35 has a downwardly extended portion 36 located in front of the table 25, and supplied with a retainer rod 37 or paper holder extended 30 transversely of the table 25. Intermediate its ends, and adjacent to the shaft 33, the arm 34 has a seat 38. The seat 38 receives one finger 39 of a coiled spring 40 engaged loosely around the shaft 33. At its inner end, the spring 40 is

provided with a finger 41 bearing against the carrier 30. The function of the spring 40 and its fingers 41 and 39 is to rotate the shaft 33 and cause the retainer 37 to bear against the copy 5 on the forward side of the table 25.

The operator places the copy on the table 25. The retainer 37 for the copy is held against the copy, by the action of the spring 40 on the arm 34 of the retainer 37. The retainer 37 can be moved up and down, that is, longitudinally and 10 vertically of the table 25, because the slide 29 can reciprocate vertically in that direction on the track 28. The retainer 37 can be swung upwardly and downwardly, in the direction of the arrows in Fig. 1, since the carrier 30 in which the shaft 15 33 is journaled is connected to the slide 29 by the pivot element 31. The retainer 37 may be moved backwardly and forwardly, toward and away from the forward surface of the table 25, to accommodate copy of different thicknesses, because the 20 shaft 33 is journaled in the ears 32 on the carrier. When the arm 34 and parts connected with it (Fig. 2) are swung backwardly, backward movement of the arm 34 is limited by engagement with a flange 32' projected laterally from 25 the outer bearing ear 32.

Having thus described the invention, what is claimed is:

In a copyholder, a table, means for supporting the table, a track on the table, a slide movable 30 along the track, longitudinally of the table, a carrier pivoted to the slide for movement about an axis at right angles to the table, a paper holder extended transversely of the table, and means for connecting the paper holder to the carrier 35 for swinging movement toward and away from the table.
